UNITED STATES PATENT OFFICE.

DANIEL F. WHITCOMB, OF LOS ANGELES, CALIFORNIA.

BILLIARD-CUE.

1,155,980.

Specification of Letters Patent.

Patented Oct. 5, 1915.

Application filed February 16, 1914. Serial No. 818,927.

To all whom it may concern:

Be it known that I, DANIEL F. WHITCOMB, a citizen of the United States, residing at the city of Los Angeles, in the county 5 of Los Angeles and State of California, have invented new and useful Improvements in Billiard-Cues, of which the following is a specification.

Heretofore when the tip of a billiard cue 10 became damaged or broken off it was necessary to remove the damaged tip and to put a new one on the cue. This was done by gluing a new tip in place if the old one was damaged too much for use. If only 15 broken off the old one was reglued in place. In either case it was necessary to clamp the tip to the cue until the glue hardened thereby rendering the cue useless until the glue hardened.

20 It is the object of my invention to so mount the tip on the cue that in case the tip becomes damaged or breaks off a new tip can be immediately attached to the cue with little loss of time and thereby restore the 25 cue to a perfect condition. I accomplish this object by the mechanism described herein and illustrated in the accompanying drawings in which:

Figure 1 is a side elevation of the end 30 of a billiard cue with my improved tip attached. Fig. 2 is a longitudinal central section of Fig. 1. Fig. 3 is an enlarged detail of the spring tube. Fig. 4 is a like detail in side elevation of the tip connector 35 and a section of the spring tube. Fig. 5 is an enlarged fragment of the tip and the tip washer and an edge view of the tip connector. Fig. 6 is an enlarged detail of the tip with the washer in section.

40 In the drawings 10 is the wooden body of a billiard cue of any desired construction except that at the tip end thereof is bored a central socket 11. In this socket is mounted a metal spring tube 12, which projects 45 slightly beyond the wooden body and in the projecting end has notches 13 in its opposite sides. In this tube is mounted an expansion spring 14, the inner end of which is secured to the inner end of tube 12. I 50 have shown it secured by portions of the tube which are clamped around the inner end of the spring. The outer end of the spring terminates in a hook 15 which when the parts are assembled for use hooks into

the eye 16 of the metal shank 17 of the tip 55 connector. This tip connector comprises a round flat head 18 of the same diameter as the spring tube and its shank 17 having eye 16 therein. The shank for a distance equal to the depth of the notch in the end of 60 the spring tube is as wide as the diameter of the tube and of a thickness to snugly fill the notch. The remaining portion of the shank snugly fits the bore of the spring tube. A 65 washer 19 of papier mâché compressed to the desired density or a leather washer compressed while wet to the desired shape has a recess 20 in the top thereof in which is received the head of the connector.

A recess 21 in the lower surface of the 70 washer receives the projecting end of the spring tube and an aperture 22 in the web between these recesses permits of the passage therethrough of the shank of the connector. Upon the top of the head of the 75 connector and to the washer is glued the usual tip 23.

In positioning the parts, after the socket 80 in the body has been bored and the spring has been secured within the spring tube, the tube is forced into the socket where it is held by friction. With an appropriate tool like a button hook the hook of the spring is engaged and then pulled till it extends beyond the end of the tube when it is temporarily secured in that position. The eye 85 of the connector is then hooked onto the spring and the spring is released thereby drawing the shank of the connector into the tube and firmly positioning the tip on the 90 end of the cue where it is held by the spring. By having a number of extra tips, in case a tip breaks or is damaged too much for use 95 it is easy to remove it and put on a new one. If desired the tip could be glued direct to the connector and the spring could be secured in any suitable manner in the socket without the use of the tube but I prefer 100 to use a washer as described and to use the tube as it renders the end of the cue stronger than without it.

Having described my invention what I claim is:

A billiard cue comprising a body having a socket in the tip end thereof; a tube 105 mounted in said socket, said tube having a notch in the outer end; a connector having a shank adapted to fit in the notch in said

tube, said shank having an eye therein; a washer secured to said connector; a tip secured to said washer; and a spring mounted in said tube and having one end secured to the tube and the other end removably connected to the connector.

5 In witness that I claim the foregoing I

have hereunto subscribed my name this 6th day of February, 1914.

DANIEL F. WHITCOMB.
